William R. S. Fluck

C. A. Brown & Co.

UNITED STATES PATENT OFFICE.

WILLIAM R. S. FLUCK, OF PALMYRA, NEW JERSEY, ASSIGNOR OF ONE-HALF
TO CHARLES F. DOLLMER, OF PHILADELPHIA, PENNSYLVANIA.

CLASP FOR UMBRELLAS.

SPECIFICATION forming part of Letters Patent No. 425,128, dated April 8, 1890.

Application filed July 3, 1889. Serial No. 316,403. (No model.)

To all whom it may concern:

Be it known that I, WILLIAM R. S. FLUCK, a citizen of the United States, residing at Palmyra, in the county of Burlington and State 5 of New Jersey, have invented a new and useful Clasp or Tying Device for Umbrellas, of which the following is a specification.

This invention relates to an improved fastening device for umbrellas; and it has for its 10 object to provide a device of this kind which shall be simple in construction and which may be easily and effectually manipulated.

My invention consists of two similarly shaped parts or members adapted to be attached, respectively, to the umbrella-cover and to the tying-strap and adapted to engage 15 each other in the manner which will be hereinafter fully described, and which will form a flat fastening that will not make an objectionable lump in the case when slipped over the umbrella, as does the ring and button clasp.

In the drawings, Figure 1 is a perspective view of a portion of an umbrella equipped with my improved fastening. Fig. 2 is a plan 20 view showing the two parts or members of my improved clasp. Fig. 3 is a side view showing the parts or members of the clasp in position to engage each other. Fig. 4 is a perspective view showing the members of the 25 clasp engaging each other. Fig. 5 is a perspective view showing the members of the clasp provided with means for attaching them in position for operation.

Like numerals of reference indicate like 30 parts in all the figures.

Each of the parts or members of my improved clasp consists, primarily, of an approximately circular plate 1, cut or stamped so as to form the shank 2 of the T-head 3 at 35 one end of the plate, and which shank is extended into and connected with the bent portion of a U-shaped head at the other end of the plate, the ends of said U-head forming tongues 4 adjacent to the said shank. The latter is provided with a bent portion or shoulder 5, by means of which the T-head 3 and the lower end of the shank are caused to lie in a plane slightly above the U-head and its 40 tongues 4 and the upper portion of the shank. It will thus be seen that when the plates or bodies 1 are placed together face to face in

position to engage each other, as will be seen in Fig. 3 of the drawings, and the said plates or bodies are then moved slightly in opposite directions, the tongues 4 of the upper clasp 55 will readily enter the slots 6 between the tongues of the lower plate and the adjacent base portion 3 of said lower plate, thus causing the plates to engage each other securely as long as any strain in opposite directions is 60 exerted upon the said plates.

The application of the fastening device as an umbrella-tie will be readily understood from the foregoing description when reference is had to Fig. 1 of the drawings. The U-head 65 of the plates is firmly secured to the umbrella-cover at the point at which the tying-strap is attached to the same, its T-head being outermost and free, and the T-head of the other plate is firmly secured at the outer end of the 70 said tying-strap with the U-head thereon free. The strap may then, when desired, be passed around the umbrella and the U-head of the plate at its outer end caused to engage the T-head of that which is secured to the umbrella-cover, as described. 75

The plates 1 may be secured in position by sewing, and they may for this purpose be provided with suitably-located perforations; or they may, when desired, be provided with 80 prongs, formed integrally therewith, as shown in Fig. 5, which said prongs may be passed through the material to which they are to be attached and then clinched or bent on the under side of the same. 85

While I have in the foregoing described my invention as being an umbrella-fastening I desire to state that it may be applied to other uses and purposes for which it may be found to be adapted—such as glove-fastenings and 90 the like—without departing from my invention.

Having thus described my invention, what I claim, and desire to secure by Letters Patent, is—

1. The herein-described umbrella-fastening, the same consisting of two duplicate interlocking plates, each comprising heads at its opposite ends standing in different planes and adapted to be applied to a strap connected at 100 one end to the umbrella and to a head of one plate and at its opposite end to the opposite

head of the other plate, as and for the purpose set forth.

2. The plate 1, comprising a **T**-head standing wholly in one plane and a **U**-head standing wholly in another plane, the shank of the **T**-head extending into the **U**-head and connecting therewith, as and for the purpose set forth.

In testimony that I claim the foregoing as my own I have hereto affixed my signature in the presence of two witnesses.

WILLIAM R. S. FLUCK.
